HINGED LOCKING DEVICE

Adelbert C. Radtke, Oak Park, Ill., assignor to
 International Harvester Company, a corpora-
 tion of New Jersey

Application April 27, 1948, Serial No. 23,552

8 Claims. (Cl. 74—535)

1

This invention relates to a locking mechanism. More specifically this invention relates to a locking device for locking and unlocking a pair of hinged members.

In certain constructions such as in clutch mechanisms, hinged closure devices, etc., it is desirable to provide hinged locking members which may be engaged in a locking position and disengaged by moving one of the hinged members successively in the same direction. In clutch mechanisms the hinged members are usually provided to engage and disengage the clutch. In closure constructions the hinged members serve to lock a closure member in various positions. Generally such a hinged locking device construction includes a stationary member having a cut-out portion. A hinged member is pivoted to the stationary member and includes a triangular wheel which has three apices designed to engage portions of the cut-out for locking the members respectively in a fixed position. In use it has been found that a triangular wheel of this type works satisfactorily for only a short period of time. The apices of a triangular wheel have but a small surface which engages the cut-out portion and these apices soon become worn and effective locking action therefore is no longer obtained. It is therefore the principal object of this invention to provide an improved locking mechanism for a pair of hinged members, said locking member being designed to provide for positive locking action despite conditions resulting from wear over a period of time.

Still another object is to provide an improved locking mechanism for a pair of hinged members, said locking mechanism being of a type which is actuated to lock and unlock said members respectively by moving one of said hinged members successively in the same direction.

A still further object is to provide an improved locking arrangement for a pair of hinged members, said locking arrangement including a stationary member having an irregular cut-out, and a hinged arm having a rectangular wheel, said wheel having opposed concave and convex surfaces adapted to cooperate with portions of the cut-out for respectively locking the hinged members and the stationary member in a fixed position.

These and other objects will become more readily apparent from a reading of the description when examined in conjunction with the drawings.

In the drawings:

Fig. 1 is a side elevational view of the hinged 55 The hinged locking device 10 includes a sta-

2

locking device shown in cooperation with a clutch throw-out mechanism.

Fig. 2 is a side elevational view similar to Fig. 1 showing the hinged locking members in an unlocked position with respect to the clutch throw-out mechanism.

Fig. 3 is a detail view showing a first and second position of the hinged locking mechanism.

Fig. 4 is a detail view showing a third and fourth locking position of said hinged members.

Fig. 5 is a detail view showing a fifth and sixth position of the hinged members.

Fig. 6 is a detail view showing the hinged members in the process of returning to their initial 15 starting position.

A hinged locking device is generally designated by the reference character 10. The hinged locking device as best shown in Figs. 1 and 2 is connected to a beam 11 and is in cooperation with a 20 clutch throw-out mechanism generally designated by the reference character 12. A pair of vertically spaced supports 13 and 14 have mounted thereon, respectively, bearings 15 and 16. The bearings 15 and 16 support for rotation thereon a line shaft 17. A sprocket 18 is mounted for rotation on the shaft 17 and has provided at one end a clutch member 19 having a clutch face 20. A clutch member 21, having a clutch face 22, is supported on the line shaft 17 and is adapted to move longitudinally with respect thereto. The clutch member 21 is keyed for rotation with the shaft 17 by means of a key 23. The key 23 is in sliding engagement with respect to a sleeve 24 which has at one end a collar 25. A spring 26 30 is positioned between the collar 25 and the bearing member 16 for normally urging the clutch member 21 into engagement with the clutch member 19.

A vertical throw-out member 27 is adapted 40 to engage the collar 25. The throw-out member 27 includes a cam surface 28 which is in engagement with the collar 25. The cam surface 28 upon upward movement of the clutch throw-out member 27 engages the collar 25 thereby compressing the spring 26 and disconnecting the clutch member 21 from the clutch member 19. An upper guide 29 and a lower guide 29' serve 45 to maintain the vertical position of the throw-out member 27. It can therefore be seen that by moving the member 27 upwardly the cam surface 28 serves to move the clutch member 21 away from the clutch member 19, whereupon turning movement of the shaft 17 is no longer imparted to the sprocket 18.

tionary member 30 which is supported on the beam 11. The stationary member 30 includes an irregular cut-out portion 31. Immediately above the irregular cut-out portion 31 there is provided a substantially vertical inclined convex cam surface 32. The cam surface 32 and a surface of the cut-out portion converge in a rounded apex 33 formed at the upper end of the cut-out portion 31. The lower end of the cut-out portion 31 is provided with a rounded projecting portion 34 as best shown in Figs. 3 to 6 inclusive. A hinged member 35 has a first arm 36 and a second arm 37 extending angularly with respect to the arm 36. The arms extend outwardly with respect to a fixed pivotal connection 38 connecting said hinged member 35 to the stationary member 30. A link 39 connects the end of the hinged member 35 to the clutch throw-out member 21.

A four-sided or rectangular locking wheel 40 is pivotally connected to the arm 37 by means of a pivot 41. The rectangular locking wheel 40 includes two opposed large concave surfaces 42 and 43 and a pair of smaller opposed concave surfaces 44 and 45. A rounded portion or apex 46 is provided between each respective concave surface. As best shown in Figs. 1 and 2, the end of the hinged member 35 is also connected to a cable 47 which is trained about an idler pulley 48 pivoted on a beam 49.

As shown in Fig. 2, the clutch members 19 and 21 are in engagement with one another and rotation of the shaft 17 will be imparted to the sprocket 18. In order to disengage the clutch member 21 from the clutch member 19, the clutch throw-out member 21 is moved upwardly, whereupon the cam surface 28 engages the collar 25 thereby moving the clutch member 21 laterally against the compression of the spring 26. By pulling on the cable 47 the hinged member 35 is initially moved in a counter-clockwise direction. The positions taken by the hinged members is best shown in Figs. 3 to 6 inclusive.

As the hinged member 35 is moved in a counter-clockwise direction, the wheel 40 is moved, whereupon the concave surface 43 is moved away from the convex cam surface 32. As shown in the broken lines of Fig. 3 the wheel 40 is moved whereupon one of the rounded inner portions 46 of the wheel comes into engagement with the rounded projecting portion 34. The wheel 40 is thereupon turned until the concave surface 45 is in mating engagement with the rounded or projecting portion 34. The operator thereupon releases his hold upon the cable 47 and the spring 26 urges the collar 25 against the cam surface 28 of the clutch throw-out member 21 thereby forcing said member downwardly. This clutch throw-out member may also be constructed to move downwardly under the direction of gravity or other means, it not being necessary to utilize the energy of the spring for this purpose. As the clutch throw-out member 21 moves downwardly, the hinged member 35 moves in a clockwise direction until the concave surface 44 comes into mating engagement with the rounded apex 33, as best shown by the dotted line position of Fig. 4, whereupon the hinged member 35 is locked with respect to the stationary member 30. The locked position, as also shown in Fig. 1, shows the clutch throw-out member 21 in its up or disengaging position.

When it is desired to re-engage the clutch member 21 with the clutch member 19, the operator again pulls on the cable 47 in a direction

shown by the arrow. The hinged member 35 therefore again moves in a counter-clockwise direction as best shown in Fig. 5. As the hinge member thus moves, one of the rounded portions 46 of the wheel 40 engages one of the surfaces of the rounded apex 33 whereupon the wheel is revolved and the concave surface 42 is placed into mating engagement with the convex surface 32. It can be seen that in any one operation the wheel 40 is revolved one half revolution. By pulling successively on the cable 47 in the same direction the hinged members can therefore be locked and unlocked at will thereby engaging and disengaging the clutch members.

It is especially important to note that the engagement of the concave surface 44 with the apices 33 provides for an effective lock. The concave surface 44 is provided at each end with the rounded surfaces 46 and it is clearly apparent that these surfaces may be subjected to wear over a period of time without adversely affecting the locking action of the wheel 40. The shape of the wheel 40 and the relation of the concave surfaces permits regular and continued use, the wearing of the surfaces of said wheel not in any way hindering the operation of the locking mechanism.

It is to be understood that the use of the locking mechanism for locking and disengaging a clutch is merely for the purpose of disclosure and is by no means limited to such an operation. The hinge locking device may be utilized in any mechanism where such a mechanical locking action is needed.

It is to be understood that changes may be made in the construction which do not depart from the spirit of the invention as disclosed nor the spirit thereof as defined in the appended claims.

What is claimed is:

1. A locking device; comprising, a stationary member; a hinge member pivotally connected to the stationary member for pivotal movement about a fixed pivot; a rectangular wheel connected for pivotal movement relative to said hinge member, said wheel having two relatively large concave surfaces positioned at two opposed sides of the wheel and two relatively smaller concave surfaces positioned at the other two opposed sides of said wheel; said stationary member having an irregular cut-out portion arranged to cooperate with the concave surfaces of said wheel; means for rotating said wheel into two successive positions whereby said wheel cooperates with said cut-out portion to relatively lock said hinge member with respect to the stationary member, and means for further rotating said wheel into two successive positions whereby said wheel is disengaged from cooperation with said cut-out portion thereby unlocking said hinge member and returning the same to its initial starting position.

2. A locking device; comprising, a stationary member; a hinge member pivotally connected to the stationary member for pivotal movement about a fixed pivot; a rectangular wheel connected for pivotal movement relative to said hinge member, said wheel having two relatively large concave surfaces positioned at two opposed sides of the wheel and two relatively smaller concave surfaces positioned at the other two opposed sides of said wheel; said stationary member having an irregular cut-out portion arranged to cooperate with the concave surfaces of said wheel; means for rotating said wheel into two

successive positions whereby said wheel cooperates with said cut-out portion to relatively lock said hinge member with respect to the stationary member.

3. A locking device comprising; a stationary member; a hinge member pivotally connected to the stationary member for pivotal movement about a fixed pivot; a wheel pivotally connected to said hinge member, said wheel having four concave side surfaces; said stationary member having a cut-out portion having a plurality of irregular surfaces arranged to engage the concave surfaces of said wheel; means for moving said hinge member in a first direction, thereby rotating said wheel into engagement with the irregular surfaces of said cut-out portion; and biased means for moving said hinge member in a second direction whereby said wheel co-acts with said stationary member for retaining said hinge member in a relative locked position.

4. A locking device comprising; a stationary member, said stationary member having a cut-out portion; a convex cam surface on said stationary member, a surface of said cut-out and said cam surface converging in a first rounded apex; a rounded portion on said cut-out portion, said rounded portion including sloping surfaces converging at a second rounded apex; a hinge member connected to said stationary member for pivotal movement about a fixed pivot; a wheel connected for pivotal movement to said hinge member, said wheel having opposed concave surfaces each being adapted to mate with the convex surface of said cam during revolution of said wheel, said wheel also including first and second substantially smaller concave surfaces, corner portions between each concave surface on said wheel, said corner portions being adapted to engage said stationary member for rotating said wheel upon movement of said hinge member, means for moving said hinge member in a first direction thereby moving said wheel and said first smaller concave surface into mating engagement with the rounded surface of said second apex and means for moving said hinge in a second direction for moving said wheel and said second concave surface into mating engagement with the surface of said first apex thereby locking said hinge member in a locked position.

5. A locking device comprising; a stationary member, said stationary member having a cut-out portion; a convex cam surface on said stationary member, a surface of said cut-out and said cam surface converging in a first rounded apex; a rounded portion on said cut-out portion, said rounded portion including sloping surfaces converging at a second rounded apex; a hinge member connected to said stationary member for pivotal movement about a fixed pivot; a wheel connected for pivotal movement to said hinge member, said wheel having large opposed concave surfaces each being adapted to mate with the convex surface of said cam during revolution of said wheel, said wheel also including first and second substantially smaller concave surfaces, corner portions between each concave surface on said wheel, said corner portions being adapted to engage said stationary member for rotating said wheel upon movement of said hinge member, first means for moving said hinge member in a first direction thereby moving said wheel and said first smaller concave surface into mating engagement with the rounded surface of second apex, resiliently biased means for moving said hinge member in a second direction for moving

said wheel and said second concave surface into mating engagement with the surface of said first apex thereby locking said hinge member in a locked position, the first means being arranged to again move said hinge member in the first direction whereby said wheel is rotated and said second concave surface is moved angularly with respect to said first apex, said resiliently biased means thereupon operating to move said hinge member again in a second direction, thereby rotating said wheel whereby one of the large concave surfaces of said wheel is in mating relation with said cam surface and said wheel is in the unlocked position.

6. A locking device comprising; a stationary member, said stationary member having a cut-out portion; a convex cam surface adjacent one end of said cut-out portion; a surface of said cut-out and said cam surface converging in a first rounded apex; a projecting portion on the other end of said cut-out portion, said projecting portion including sloping surfaces converging at a second rounded apex; a hinge member connected to said stationary member for pivotal movement about a fixed pivot; a wheel connected for pivotal movement to said hinge member, said wheel having two opposed large concave surfaces each being adapted to mate with the convex surface of said cam during one half revolution of said wheel, said wheel also including first and second substantially smaller concave surfaces, corner portions between each concave surface on said wheel, said corner portions being adapted to engage portions of said stationary member for rotating said wheel upon movement of said hinge member, first means for moving said hinge member in a counter-clockwise direction thereby moving said wheel and said first smaller concave surface into mating engagement with the rounded surface of said second apex, second means for moving said hinge in a clockwise direction for moving said wheel and said second concave surface into mating engagement with the surface of said first apex thereby locking said hinge member in a locked position, the first means being arranged to move said hinge member in a counter-clockwise direction whereby said wheel is rotated and said second concave surface is moved angularly with respect to said first apex, said second means thereupon operating to move said hinge member again in a clockwise direction, thereby rotating said wheel whereby one of the larger concave surfaces of said wheel is in mating relation with said convex cam surface and said wheel is in the unlocked position.

7. A locking device comprising; a stationary member, said stationary member having an irregular cut-out portion; a substantially vertically inclined convex cam surface adjacent one end of said cut-out portion; a surface of said cut-out and said cam surface converging in a first rounded apex; a projecting portion on the other end of said cut-out portion, said projecting portion including sloping surfaces converging at a second rounded apex; a hinge member connected to said stationary member for pivotal movement about a fixed pivot; a wheel connected for pivotal movement to said hinge member, said wheel having two opposed large concave surfaces, each being adapted to mate with the convex cam surface during one half revolution of said wheel, said wheel also including first and second substantially smaller concave surfaces, rounded corner portions between each concave surface on said wheel, said corner portions being adapted to en-

gage said cut-out and projecting portions for rotating said wheel upon movement of said hinge member, first means for moving said hinge member in a counter-clockwise direction thereby moving said wheel and said first smaller concave surface into mating engagement with the rounded surface of said second apex, second means for moving said hinge member in a clockwise direction for moving said wheel and said second concave surface into mating engagement with the surface of said first apex thereby locking said hinge member in a locked position, the first means being arranged to again move said hinge member in a counter-clockwise direction whereby said wheel is rotated and said second concave surface is moved angularly with respect to said first apex, said second means thereupon operating to move said hinge member again in a clockwise direction, thereby rotating said wheel whereby one of the large concave surfaces of said wheel is again placed into mating relation with said cam surface and said hinge member and said stationary member are respectively in an unlocked position.

8. A locking device comprising: a stationary member, said stationary member having an irregular cut-out portion; a substantially vertically inclined convex cam surface adjacent one end of said cut-out portion; a surface of said cut-out and said cam surface converging in a first rounded apex; a projecting portion on the other end of said cut-out portion, said projecting portion including sloping surfaces converging at a second rounded apex; a hinge member connected to said stationary member for pivotal movement about a fixed pivot, said hinge member having arm portions extending outwardly at either sides of said fixed pivot; a wheel connected for pivotal movement to one of said arm portions, said wheel having two opposed concave surfaces, each being adapted to mate with the convex cam surface

during one half revolution of said wheel, said wheel also including first and second substantially smaller concave surfaces, rounded corner portions between each concave surface on said wheel, 5 said corner portions being adapted to engage said cut-out and projecting portions on the stationary member for engaging and rotating said wheel upon movement of said hinge member in a counter-clockwise direction thereby moving said wheel and said first smaller concave surface into mating engagement with the rounded surface of said second apex, resiliently biased means for moving said hinge member in a clockwise direction whereby the wheel engages the cut-out portion 10 and moves said second smaller concave surface into mating engagement with the surface of said first apex thereby locking said hinge member in a locked position, means for unlocking said hinge member including means for moving said hinge member in a counterclockwise direction whereby 15 said wheel engages a projecting portion on the stationary member and is rotated and said second concave surface is moved angularly with respect to said first apex, said resiliently biased means thereupon operating to move said hinge member again in a clockwise direction, thereby rotating said wheel whereby one of the concave surfaces of said wheel is again placed in mating relation with said cam surface and said wheel 20 is in an unlocked position.
